RESILIENT CLIP

John P. Walsh, Norwood, R.I.

Application January 16, 1958, Serial No. 49,268

Term of patent 14 years

(Cl. D17—3)

Fig. 1

Fig. 2

Fig. 3

Fig. 4

Fig. 5

Fig. 1 is a rear elevational view of a resilient clip embodying the instant design;

Fig. 2 is a side elevational view thereof;

Fig. 3 is a front elevational view thereof;

Fig. 4 is a top view thereof; and

Fig. 5 is a bottom view thereof.

I claim:

The ornamental design for a resilient clip, substantially as shown.
